SHEDDING MECHANISM FOR LOOMS

Leopold Fuchs, North Bergen, N. J.

Application January 30, 1941, Serial No. 376,703

8 Claims.

(Cl. 139—69)

This invention appertains to shedding mechanisms for looms, and more especially to an improved harness construction and control means therefor as applied to shaft weaving.

One of the primary objects of the invention is to provide a novel form of shaft harness which is of such simple and compact form as to permit the assembly of a far greater number of the same in the space required at present for a much less number. For example, I am able to assemble up to sixty or more of my improved harness shafts in the same space that twenty-five of the conventional type now require. This results not only in the important advantage of conserving space, but also more particularly, in simplifying the weaving of complicated or fancy designs, and with greater prominence of the design of the weave.

Another novel feature of the invention resides in the simplification of the harness from the standpoint of changing of heddles which can be performed with my improved harness while the warp is entered through the entire width of the harness, and in the shortest possible time.

A still further object of the invention is to provide a shaft harness mechanism which admits of the use of relatively long heddles resulting in easier handling by the operator and greater flexibility of the harness so as to eliminate rubbing and chafing which usually causes frequent breakages of the warp threads, especially when these are silk, rayon or some inferior grade of material. To this end, my invention contemplates among other things the actuation of the harness shafts and heddles in such manner that the warp threads in passing from one line of the shed to the other do not all pass the center at the same time, and which admits of simple and quick adjustment as the conditions may require.

Still another object of the invention is to provide an improved rise and fall system which creates a materially improved and efficient shed, and enables the weaving of the most fancy or brocade weaves in an economical and convenient manner.

Another object of the invention is to provide an improved griff blade construction and actuating means for the same, serving to control the harness shafts.

Other and further objects and advantages of the invention will be hereinafter described and the novel features thereof defined by the appended claims.

In the drawings:

Figure 1 is a fragmentary view in front elevation of a harness mechanism constructed in accordance with my invention, certain of the heddles being omitted;

Figure 2 is a view partly in section and partly in side elevation of the harness control mechanism or rise and fall system which serves to produce the rise and fall motion of the harness shafts in forming the shed;

Figure 3 is a view generally similar to Figure 2, and constituting a section through the control mechanism generally parallel to the griff blades to show more clearly the improved griff blade construction, certain of the griff blades being shown in their inactive position;

Figure 4 is a fragmentary view in top plan of the griff blades and associated cam actuating means, certain parts being broken away and shown in section;

Figure 5 is a sectional view taken on the line 5—5 of Figure 4;

Figure 6 is a detailed view of the eccentric sheaves which form a part of the rise and fall control mechanism for the harness shafts;

Figure 7 is a detail view of one of the cams of the griff blade actuating mechanism;

Figure 8 is a fragmentary enlarged detail view in front elevation of the upper portion of one harness and showing the heddles attached to the heddle shaft, a portion of the harness shaft being broken away and shown in section;

Figure 9 is a fragmentary sectional view taken on the line 9—9 of Figure 1;

Figure 10 is a sectional view taken on the line 10—10 of Figure 8;

Figures 11 and 12 are sectional views taken respectively on the lines 11—11 and 12—12 of Figure 8; and

Figure 13 is a perspective view of an auxiliary heddle carrier which serves to permit interchange of certain heddles in a group without detaching the heddles individually.

Like reference characters designate corresponding parts in the several figures of the drawings.

It is to be understood at the outset that the features of improvement to which my invention relate are applicable to various types of looms, including the conventional dobby looms and Jacquard looms, and such looms may be converted for shaft weaving by suitable modification and substitution of the features herein-after described. Since the main parts of the loom are well known and are more or less im-

material to the present invention, they have not been illustrated or described herein, and my application has been largely confined to the shedding mechanism and associated elements with which the improvements are more particularly concerned.

Referring to Figure 1, the reference character 1 designates the conventional supporting frame or super-structure which is usually provided on a dobby loom to serve as a mounting for the head motion. In the present invention, this supporting frame 1 carries the harness mechanism which includes a plurality of harness shafts 2 arranged one behind the other in closely assembled relation. Only one set of shafts is necessary for each loom, but the number of shafts will vary according to the requirements for the particular weave or design to be produced. Due to my improved harness shaft construction, each shaft is comparatively light in weight and of simple form, being preferably composed of sheet metal folded upon itself as best illustrated in Figure 11. Attached at spaced intervals to the shaft 2 and depending therefrom are hooks 3, also preferably composed of sheet metal with the bight of the hooks opening in an upward direction to receive a carrier bar 4. The form of the hooks will be best understood from reference to Figure 10. The carrier bar 4 may be composed of a solid bar, or it may be made in separable sections, as preferred, and serves to carry the heddles which are designated 5. To attach the heddles to the carrier bar 4, and consequently to the harness shaft 2, I preferably provide a simple though novel type of self-closing hook 6 which is best shown in Figures 12 and 13. These hooks 6 may be made of relatively stiff wire and are each provided with an eye 7 at its lower end which is attached to the upper end of a cord 8. The lower end of each cord 8 is attached to the upper end of a heddle 5. The upper end of each hook 6 includes a portion 9 bent over and lying at a slight angle to the shank of the hook, and the free extremity 10 of the hook is bent towards the shank so as to normally lie close thereto when the hook is closed. The material of which the hooks 6 are formed should have sufficient stiffness and resiliency to maintain the shape of the hook as just described, and to cause the hook to be self-closing. By forcing the free extremity 10 of the hook away from the shank of the hook, the hook may be quickly and easily removed from the carrier bar 4 or applied on to the same as the occasion requires.

Attached to the lower end of each heddle 5 is a lingoe or weight 11 which serves to impose a small weight or tension onto the lower end of the heddle and keep it in a more or less vertical position. By reason of the harness construction as just described, I am able to employ heddles of the one piece type and having a length of 36 inches, more or less, as desired. This imparts a much greater flexibility to the harness than is normally afforded in the conventional harness constructions, and minimizes breakage of the warp (not shown) entered through the heddles, especially in the case of heavily entered heddles and reeds.

While the hooks 6 permit simple and rapid interchange of the position of any heddle or heddles, or the complete removal of individual heddles, all while the warp remains entered through the entire width of the harness, I preferably provide an auxiliary carrier bar 4' having a hook 3' attached thereto at its respective ends to en-

able the auxiliary carrier bar 4' to be hooked onto the carrier bar 4 at any position in the length of the latter to support a group of heddles so that they may be interchanged, added, or removed without handling the heddles individually. The hooks 6 attached to the upper ends of the respective heddles of the group may be the same as those which are applied directly to the carrier bar 4, but to compensate for the difference in the position of the auxiliary carrier bar 4', which is below the main carrier bar 4, the cords 8' shown in Figure 13 should be tied shorter, thus bringing the warps entered through the group of heddles in the same initial plane as those entered through the heddles which are suspended directly from the main carrier bar 4.

In order to suitably space the harness shafts 2 from each other and permit their passing without interference with each other during the rise and fall motion of the respective shafts, I preferably provide a guide frame generally designated 12, at each end of the loom and composed of a plurality of spaced bars 13. The bars 13 of the guide frame 12 are arranged in vertical parallel relation to each other and are spaced apart in a direction transversely of the harness shafts so that the opposite ends of the respective harness shafts 2 and their corresponding carrier bars 4 are received in the spaces between the bars 13, forming ways in which the carrier bars and harness shafts are guided in the upward and downward motion of the latter. The upper and lower ends of the bars 13 are respectively assembled on the rods 14 and 15 which form a part of the guide frame 12, and the upper end of each guide frame is preferably adjustably supported at 16 so as to be movable both laterally and longitudinally relative to the loom frame 1, as will be best understood from reference to Figure 1. While the hooks 3 which receive the carrier bars 4 are preferably so constructed as to closely embrace the carrier bars when disposed in the hooks, the gripping action of the hooks should not be so great as to prevent complete removal of the carrier bars when the occasion demands. To prevent lateral displacement of the carrier bars 4 to one side or the other of the loom during the weaving operation, pins 17, 17 are disposed in the respective opposite ends of the carrier bars and adjacent to the guide frames 12.

Provision is also preferably made for preventing transverse displacement of the respective harness shafts 2 during the rise and fall motion of the latter. To this end, there is attached to one or both ends of each harness shaft 2 an arm 18 carrying a vertically disposed elongated guide bar 19 having its upper extremity offset laterally outwardly as at 20. Rotatably mounted intermediate each guide bar 19 and the adjacent side of the loom frame 1 is a grooved guide roller 21 in which the guide bar 19 seats, allowing free movement of the harness shaft 2 and guide bar 19 in an upward and downward direction. The upper offset end 20 of the guide bar 19 limits the downward movement of the harness shaft 2.

Attached to the upper edge of each harness shaft 2 adjacent to each end of the shaft is a hook 22 by means of which the harness shafts may be removably attached to the rise and fall system now to be described. As best shown in Figure 8, each hook 22 is provided at its lower end with a laterally offset part 22' which is received through an opening in the upper edge of the shaft and lies within the base of the fold of

the sheet metal from which the shaft is formed, thus effectively supporting the shaft from the upper end of the hook without imposing undue strain upon a too limited surface or portion of the metal of the shaft. Attached to each hook 22 is a flexible connector 23, preferably having the form of a chain. Each chain 23 for the corresponding pair of hooks 22 of each harness shaft 2 extends upwardly from the respective hooks and is trained over an eccentric sheave 24 mounted upon and located above the upper end of the supporting frame 1. The sheaves 24 are carried by shafts 25, 25 and are free to rotate on their respective shafts. The opposite ends of the shafts 25, 25 are adjustably supported by stands 26, 26 which in turn are adjustably secured to the top of the frame 1 so as to permit adjustment of the respective stands 26 both laterally and transversely of the frame 1. Provision is also preferably made for adjusting the elevation of the shafts 25 in the stands 26 as will be best understood from reference to Figure 1.

From the foregoing, it will be recognized that a pair of sheaves 24, 24 is provided for each harness shaft 2, corresponding to the pair of chains 23, 23 from which each shaft is suspended. Each sheave 24 is also preferably provided with spaced pins or sprocket teeth 27 about its periphery for engagement in the links of the corresponding chain 23. Due to the eccentric construction of the sheaves 24, 24, the rise and fall of the harness will be accelerated or retarded during the formation of the shed, but the still more important advantage is attained by making it possible to simply and quickly adjust the throw of the eccentric sheaves in timing the different harnesses of the entire set used so that the warp threads in passing from one line of the shed to the other will not all pass the center at the same time. This has the important advantage of minimizing rubbing and chafing of the warp threads, resulting in breakage of the threads to which silk, rayon and inferior grades of materials are so susceptible.

Referring now more particularly to Figures 2 to 5 inclusive, the ends of each pair of chains 23, 23 opposite to the ends which are attached to the hooks 22, 22 of the respective harness shafts 2, are attached to a griff blade 28. To facilitate the connection of the chains to their griff blades, I preferably provide a special form of connector 29 best shown in Figure 3 and comprising a clip having interlocking engagement at one end with the end of the griff blade, and having a double socket in its opposite end at 29', 29'' to receive the respective chains 23 of the corresponding pair.

It is understood that there is one griff blade for each harness shaft. The griff blades are assembled in a frame designated 30 which is attached to or otherwise supported at one side of the loom frame 1. Rotatably mounted in the frame 30 is a shaft 31 which may be driven from any convenient rotary part of the loom or main driving mechanism (not shown). At the front and back of the frame 30 and fixed to the shaft 31 for rotation therewith is a pair of cams 32, 33. The cam 33 engages a follower 34 which is mounted on one end of a bar 35, the bar 35 in turn being connected to a griff bar 36 positioned at one end of the frame 30 and slidably mounted thereon. The griff bar 36 extends across the frame 30 from front to back, and carries at its opposite ends guide blocks 37 adapted to work in guide

ways 38 formed in the respective front and rear sides of the frame 30. As shown best in Figure 4, the bar 35 extends through the guide block 37 and is fixed thereto by the jam nuts 39 and 40, while the guide block 37 is in turn attached to the end of the griff bar 36 by the screw 41. This assembly is duplicated at both ends of the griff bar.

Cooperating with the cam 32 is a second bar 42 which carries spaced followers 43, 44 and is provided with an elongated slot 45 through which the shaft 31 extends to permit free reciprocation of the bar 42 incident to rotation of the cam 32. The bar 42 is in turn connected to a second griff bar 46 disposed at the end of the frame 30 opposite to the griff bar 36. The connection of the bar 42 with the griff bar 46, and the slidably mounting of the griff bar 46 in the frame 30 is similar to that described above in relation to the bar 35 and griff bar 36, and hence need not be repeated at this point. Suffice it to say that the bar 42 and guide block 47 by which the same is connected to the griff bar 46 is duplicated at each end of the griff bar 46 for actuation by a corresponding cam 32. The free ends 35' and 42' of the respective connecting bars 35 and 42 are preferably guided in suitable ways provided in the frame 30 as will be best understood from reference to Figure 2.

As will also be seen from Figures 2 and 4, the cams 32 and 33 on the shaft 31 are set in opposed relation to each other so as to impart reciprocating motion to the respective griff bars 36 and 46 in opposed timed relation. While these cams 35 may be of the same size, I preferably so construct the cams as to permit variation of the motion transmitted to the griff bars when such variation is desired. To this end, each cam may be supplied with removable cam segments 48 which may be interchanged with other segments of different shape. The detachable segments are illustrated in Figure 7, showing one segment 48 attached to one of the cams 32 or 33, as the case may be, by means of the recessed bolts 49.

In order to establish an operative connection between the griff bars 36 and 46 and the griff blades 28, the griff blades are assembled in the frame 30 in horizontal, parallel relation to each other. Each griff blade is guided by a pair of grooved rollers 50, 50 rotatably mounted at one end of the frame 30 as shown in Figures 2 and 3. Each griff blade is preferably made in two sections 28' and 28'', which are pivotally connected together at 51. The section 28' is provided with a hook 52 adjacent to the pivotal connection 51, and the section 28'' is likewise provided with a hook 53 at its free extremity. The hook 52 contacts with the griff bar 46, and the hook 53 similarly contacts with the griff bar 36. For example, as the griff bar 46 moves to the right as viewed in Figure 3 (while at the same time the griff bar 36 is moving to the left) the hook 52 will be engaged by the griff bar 46 to transmit the motion of the griff bar to the griff blade sections 28' and 28'', which in turn are attached to the chains 23, 23 from which one of the harness shafts is suspended, resulting in a rising motion being imparted to the harness shaft. As the griff bar 46 moves to the left from the dotted line position illustrated in Figure 3, the griff blades which are engaged with this griff bar will correspondingly move to the left, because of the weight of the harness shafts which normally tends to urge the griff blades to the left. In other words, after each pick, the griff bars 46 and 36 are in the dot-

ted line positions shown in Figure 3, and all the hooks 52 are in engagement with the griff bar 46, all the warp threads being in the same plane. When the griff bar 46 moves to the left, the lines will lower the warp threads out of the aforesaid plane and cause the hooks 52 to follow the griff bar 46, except those on the griff blades which are moved by the griff bars 36 engaging hooks 53 on its movement to the right, thus raising selected warp threads out of the aforesaid plane and forming the shed as in split shedding.

Since all the hooks 52 are in engagement with the griff bar 46 when the bar is in dotted line position, only those hooks 52 can be in engagement with it in full line position which have their griff blade hooks 53 elevated by the needles 55 of the pattern mechanism out of engagement with the griff bar 36. When it is desired to render any particular griff blade or group of griff blades inactive, this may be simply and quickly done by engaging the pre-determined griff blade sections 28' with a stationary bar 54 which is fixed to the frame 30 as illustrated in Figure 3. These griff blades which may not be needed for certain weaves may thereby be conveniently disposed of, while they are always readily accessible when it is desired to restore the same to an active position. The particular construction of the griff blades as just described is possessed of considerable strength necessary to control the rise and fall motion of my improved harness mechanism. The enlarged head or hook on the end of each griff blade section 28' has the further advantage of strengthening the joint between the griff blade sections and assures accurate alignment of the sections 28', 28'' relative to each other, while at the same time the grooved rollers 50, 50 engaging each griff blade serve to maintain easy, straight, and steady reciprocating movement of the griff blades.

It will be understood, of course, that the griff blades may be controlled by any suitable pattern mechanism which is generally represented in Figure 3 by the needle 55 disposed beneath each of the griff blade sections 28'' so that when the needles 55 are raised in any pre-determined order, they will impart a corresponding elevating movement to the pre-determined griff blade sections 28'' and thereby move the hooks 53 of these griff blade sections out of the path of the griff bar 36.

The operation of the invention should be clear from the foregoing description, and accordingly need not be repeated. It may be well, however, to emphasize that each harness shaft may be timed independently of the others, and this in a most simple and effective way. To form an uneven lift as is very profitable in the case of heavily entered harnesses and reeds, it is merely necessary to raise the chains 23 to a position temporarily out of engagement with the eccentric sheaves 24 and then set the sheaves to any angular position desired. This simple adjustment is permitted by reason of the fact that all of the sheaves on each shaft 25 are loosely carried by the shaft and are free to be rotated relative to each other.

By reason of the novel combination of elements which enter into my invention, all types of bindings and an unlimited range of figures or designs can be produced, as contrasted with the usual limitations imposed upon conventional looms, some of which can produce only a single type of binding known as taffeta, and a very limited range of variation of figure.

While the specific details have been herein shown and described, the invention is not confined thereto as changes and alterations may be made without departing from the spirit thereof as defined by the appended claims.

What I claim as new and desire to secure by Letters Patent is:

1. In a shed operating mechanism for shaft looms having a plurality of harnesses arranged for movement in an upward and downward direction in timed relation to raise and lower selected warp threads entered through said harnesses relative to a common plane to form the shed, a plurality of jointed griff blades, one for each harness, supported at one side of the loom in parallel relation to each other for horizontal reciprocating movement, a pair of flexible motion-transmitting members directly interconnecting one end of each griff blade to laterally spaced points of the shaft of a corresponding harness, a pair of eccentric sheaves for each harness rotatably supported above the corresponding shafts in laterally spaced relation to each other and with their axes of rotation arranged perpendicular to the plane of the harness, said flexible motion-transmitting members of each harness being trained over the respective eccentric sheaves, and the sheaves for the respective harnesses being rotatively displaced relative to one another so that on raising and lowering the harnesses by the motion imparted thereto by the flexible members trained over the sheaves, the warp threads entered through the harnesses will not pass the center of the shed at the same time as the warp threads are shifted from one line of the shed to the other by the reciprocating movement of the griff blades, a pair of horizontally reciprocable griff bars arranged transversely of the griff blades in spaced parallel relation to each other and movable in opposed timed relation lengthwise of the griff blades, abutment means on the jointed sections of each griff blade respectively disposed in the path of movement of the griff bars to produce reciprocating movement of the griff blades by either of the griff bars, means for selectively displacing the jointed sections of the griff blades to disengage their abutment means from one of the griff bars while reciprocating motion is transmitted to those griff blades by the other griff bar, and means for reciprocating the griff bars.
2. Apparatus as defined in claim 1, wherein the eccentric sheaves of the respective pairs of sheaves are rotatably adjustable independently of each other to vary the throw thereof, and thereby permit independent timing of the harnesses.
3. Apparatus as defined in claim 1, wherein the flexible connectors and sheaves have positive, anti-slipping engagement with each other.
4. Apparatus as defined in claim 1, wherein the flexible connectors have the form of open-link chains, and the sheaves are provided with circumferentially spaced projections on their peripheries to positively engage the chains.
5. In a shed operating mechanism for shaft looms having a plurality of harnesses arranged for movement in an upward and downward direction in timed relation to raise and lower selected warp threads entered through said harnesses relative to a common plane to form the shed, a plurality of jointed griff blades, one for each harness, supported at one side of the loom in parallel relation to each other for horizontal reciprocating movement, a pair of flexible motion-transmitting members directly interconnecting one end of each griff blade to laterally spaced

points of the shaft of a corresponding harness, a pair of eccentric sheaves for each harness rotatably supported above the corresponding shafts in laterally spaced relation to each other and with their axes of rotation arranged perpendicular to the plane of the harness, said flexible motion-transmitting members of each harness being trained over the respective eccentric sheaves, and the sheaves for the respective harnesses being rotatively displaced relative to one another so that on raising and lowering the harnesses by the motion imparted thereto by the flexible members trained over the sheaves, the warp threads entered through the harnesses will not pass the center of the shed at the same time as the warp threads are shifted from one line of the shed to the other by the reciprocating movement of the griff blades, a pair of horizontally reciprocable griff bars arranged transversely of the griff blades in spaced parallel relation to each other and movable in opposed timed relation lengthwise of the griff blades, abutment means on the jointed sections of each griff blade respectively disposed in the path of movement of the griff bars to produce reciprocating movement of the griff blades by either of the griff bars, means for selectively displacing the jointed sections of the griff blades to disengage their abutment means from one of the griff bars while reciprocating motion is transmitted to those griff blades by the other griff bar, and cam means for reciprocating the griff bars.

6. In a shed operating mechanism for shaft looms having a plurality of harnesses arranged for movement in an upward and downward direction in timed relation to raise and lower selected warp threads entered through said harnesses relative to a common plane to form the shed, a plurality of jointed griff blades, one for each harness, supported at one side of the loom in parallel relation to each other for horizontal reciprocating movement, a pair of flexible motion-transmitting members directly interconnecting one end of each griff blade to laterally spaced points of the shaft of a corresponding harness, a pair of eccentric sheaves for each harness rotatably supported above the corresponding shafts in laterally spaced relation to each other and with their axes of rotation arranged perpendicular to the plane of the harness, said flexible motion-transmitting members of each harness being trained over the respective eccentric sheaves, and the sheaves for the respective harnesses being rotatively displaced relative to one another so that on raising and lowering the harnesses by the motion imparted thereto by the flexible members trained over the sheaves, the warp threads entered through the harnesses will not pass the center of the shed at the same time as the warp threads are shifted from one line of the shed to the other by the reciprocating movement of the griff blades, a pair of horizontally reciprocable griff bars arranged transversely of the griff blades in spaced parallel relation to each other and movable in opposed timed relation lengthwise of the griff blades, abutment means on the jointed sections of each griff blade respectively disposed in the path of movement of the griff bars to produce reciprocating movement of the griff blades by either of the griff bars, means for selectively displacing the jointed sections of the griff blades to disengage their abutment means from one of the griff bars while reciprocating motion is transmitted to those griff blades by the other griff bar, and means for reciprocating the griff bars.

7. In a shed operating mechanism for shaft looms having a plurality of harnesses arranged for movement in an upward and downward direction in timed relation to raise and lower selected warp threads entered through said harnesses relative to a common plane to form the shed, a plurality of jointed griff blades, one for each harness, supported at one side of the loom in parallel relation to each other for horizontal reciprocating movement, a pair of flexible motion-transmitting members directly interconnecting one end of each griff blade to laterally spaced

10 points of the shaft of a corresponding harness, a pair of eccentric sheaves for each harness rotatably supported above the corresponding shafts in laterally spaced relation to each other and with their axes of rotation arranged perpendicular to the plane of the harness, said flexible motion-transmitting members of each harness being trained over the respective eccentric sheaves, and the sheaves for the respective harnesses being rotatively displaced relative to one another so that on raising and lowering the harnesses by the motion imparted thereto by the flexible members trained over the sheaves, the warp threads entered through the harnesses will not pass the center of the shed at the same time as the warp threads are shifted from one line of the shed to the other by the reciprocating movement of the griff blades, a pair of horizontally reciprocable griff bars arranged transversely of the griff blades in spaced parallel relation to each other and movable in opposed timed relation lengthwise of the griff blades, abutment means on the jointed sections of each griff blade respectively disposed in the path of movement of the griff bars to produce reciprocating movement of the griff blades by either of the griff bars, pattern-controlled means for selectively displacing the jointed sections of the griff blades to disengage their abutment means from one of the griff bars while reciprocating motion is transmitted to those griff blades by the other griff bar, and means for reciprocating the griff bars.

8. In a shed operating mechanism for shaft looms having a plurality of harnesses arranged for movement in an upward and downward direction in timed relation to raise and lower selected warp threads entered through said harnesses relative to a common plane to form the shed, a plurality of jointed griff blades, one for each harness, supported at one side of the loom in parallel relation to each other for horizontal reciprocating movement, a pair of flexible motion-transmitting members directly interconnecting one end of each griff blade to laterally spaced points of the shaft of a corresponding harness, a pair of eccentric sheaves for each harness rotatably supported above the corresponding shafts in laterally spaced relation to each other and with their axes of rotation arranged perpendicular to the plane of the harness, said flexible motion-transmitting members of each harness being trained over the respective eccentric sheaves, and the sheaves for the respective harnesses being rotatively displaced relative to one another so that on raising and lowering the harnesses by the motion imparted thereto by the flexible members trained over the sheaves, the warp threads entered through the harnesses will not pass the center of the shed at the same time as the warp threads are shifted from one line of the shed to

the other by the reciprocating movement of the griff blades, a pair of horizontally reciprocable griff bars arranged transversely of the griff blades in spaced parallel relation to each other and movable in opposed timed relation lengthwise of the griff blades, abutment means on the jointed sections of each griff blade respectively disposed in the path of movement of the griff bars to produce reciprocating movement of the griff blades by either of the griff bars, means for selectively dis-

placing the jointed sections of the griff blades to disengage their abutment means from one of the griff bars while reciprocating motion is transmitted to those griff blades by the other griff bar, means for reciprocating the griff bars, and means engageable at will by the pivotal sections of selected griff blades to hold said griff blades in an inactive position with their abutments displaced out of engagement with both griff bars.

LEOPOLD FUCHS.
